CURTAIN AND DRAPERY ROD

Landen D. Smith, Richmond Hill, N. Y.

Application December 22, 1933, Serial No. 703,516

4 Claims. (Cl. 156—22)

The invention relates to rods for supporting curtains and draperies. It has for its main object to provide a curtain and drapery rod having brackets which, without the use of any nails, screws or other fastening means, can be attached to the top casing of any window, door or similar object which it may be desired to drape.

Another object is to provide a rod to which other rods, of various lengths, may be attached, either in the same plane or at various heights, so as to make possible a great many combinations suitable for any arrangement of the draperies. A further object is to provide various accessories with the rods to maintain the draperies in certain positions, to enable them to be drawn back and forth, to be suspended at various heights in relation to the rods, and for other purposes which will be explained later. An additional object is to provide a set of curtain rods which can be manufactured and sold at a comparatively low price.

These and other objects and advantages will be readily understood from the following description and from the accompanying drawing of a preferred embodiment of the invention in which, however, modifications may be made without departing from the scope of the appended claims. In the drawing

Fig. 1 is a front view illustrating certain of the combinations in which the rods may be arranged,

Fig. 2 is a top view of Fig. 1,

Fig. 3 a side view of one of the bracket hangers,

Fig. 4 a front view of Fig. 3,

Fig. 5 a side view of a rod bracket,

Fig. 6 a front view of Fig. 5,

Fig. 7 a side view of a modified bracket hanger,

Fig. 8 a side view of a modified rod bracket,

Fig. 9 a front view of Fig. 8 shown with frag-

ments of the rods attached,

Fig. 10 a rear view of one of the rods shown with certain accessories attached therein,

Fig. 11 a side view of one of these accessories,

Fig. 12 an end view of a rod and of another of these accessories, and

Fig. 13 a fragmental rear view of two rods connected together.

Figs. 10, 11, 12 and 13 are drawn to a larger scale than the remaining views.

Referring now to all the views, the rods, which are shown at 1A, 1B and 1C, are preferably made of sheet metal and have their edges bent rearwardly and inwardly towards each other so as to form two flanges 2 and 3. The cross-sectional shape of the rods is clearly shown in Fig. 12.

Figs. 3 and 4 show one embodiment of one of

the bracket hangers used for supporting the rods. It consists of a strip of metal 4 on which a hook 5 is formed on the upper end. The extreme end 6 of the hook is bent downwardly so as to engage on the top of the top casing of any window, door or the like. The end 6 is preferably serrated as shown at 7. A forwardly extending bracket 8 is secured below the hook. The outer end of this bracket is slit and the extreme ends bent in opposite directions so as to form tongues 9 and 10. These tongues will slide freely in any of the rods and are kept in place by the flanges 2 and 3. The modified bracket hanger shown in Fig. 7 is similar to the one just described, except that it is made from a single strip of metal.

Figs. 5 and 6 show one of the rod brackets employed for attaching several rods to each other. This bracket is also preferably made of a strip of metal 11 and it is shaped in the manner shown. Both its ends are slit and formed into tongues 12, 13 and 14, 15 which will also slide freely in any of the rods. In Fig. 6 the tongues 12 and 13 are engaged in the rod 1A, while the tongues 14 and 15 are free to receive another rod. It will be noted that with this rod bracket the rods are all supported at the same height, while with the modification shown in Figs. 8 and 9 the rods 1A and 1B are at different heights.

Referring now to Figs. 10, 11, 12 and 13 in which various accessories are illustrated, Fig. 10 shows a rear view of any one of the rods in which a retaining hook 16 is employed. The hook is made of spring wire and provided with two arms 17 and 18 which frictionally clamp in the rod. An end view of this hook is shown in Fig. 12. A drapery hanger 19 is shown in Figs. 10 and 11. It consists of a wire bent as shown and provided with eyelets 20 and 21. Fig. 13 illustrates how any of the rods may be connected together by means of a splice rod 22.

The various ways in which this set of rods may be used and assembled will now be described. The rods may be inserted in hems in the curtains in the usual manner and the curtains may be completely arranged on the rods before these are put up. After the curtains are arranged on the rods, the bracket hangers are attached to a rod and the ends of these hangers hung on the top of the top casing 23 with the serrations 7 resting thereon. The shape of the bracket hangers enable them to carry considerable weight without being displaced from the top casing, and no fastening means are necessary. This makes it very easy to hang the curtains and prevent the mar-

ring of the casing as when nails or screws are used.

When it is desired to use double rods, the tongues 12 and 13 of either of the rod brackets shown in Figs. 5 and 8 are inserted in the rod 1A and the second rod 1B attached on the tongues 14 and 15. The second rod may be of the same length as the first, or one or more short rods may be used as shown by 1C in Figs. 1 and 2. Any number of rods may be attached to each other by means of these rod brackets and, as previously explained, the rods may be arranged at the same or different heights, as shown in Fig. 9.

Instead of attaching the curtains or draperies directly to the rods, they may be attached to hangers 19 such as shown in Figs. 10 and 11. These hangers slide freely in the rods. To prevent the curtains or draperies from sliding on the rods, hooks, such as shown at 16 in Figs. 10 and 12, are employed. The arms 17 and 18 of these hooks exert sufficient pressure against the rod to prevent movement of the hooks, even when heavy draperies are used. The part 22, shown in Fig. 13, provides an easy means for joining several rods, as for example when it is desired to span several windows.

From the foregoing it will be seen that this set of rods allows a great many combinations to be made, that it is simple to manipulate, and inexpensive to manufacture.

Having described my invention and its objects, what I claim as new and wish to protect by Letters Patent is:

1. A curtain rod set comprising a rod having a dovetailed groove, a plurality of bracket hangers having members slidably engageable in said

groove and provided with hooks at their upper end for engagement with the top of a window casing or similar object, and a plurality of brackets each having one end engageable in said dovetailed groove and the other end adapted to support another rod on the same plane with the first-mentioned rod. 5

2. A curtain rod set comprising a rod having a dovetailed groove, a plurality of bracket hangers having members slidably engageable in said groove and provided with hooks at their upper end for engagement with the top of a window casing or similar object, and a plurality of brackets each having one end engageable in said dovetailed groove and the other end adapted to support another rod on a different plane than that of the first-mentioned rod. 15

3. A curtain rod set comprising a rod having a dovetailed groove, a plurality of bracket hangers having members slidably engageable in said groove and provided with hooks at their upper end for engagement with the top of a window casing or similar object, a plurality of brackets each having one end engageable in said dovetailed groove and the other end adapted to support a second rod, and the second rod similarly dovetailed to receive additional brackets supporting additional rods. 20

4. A curtain rod having a dovetailed groove, a plurality of bracket hangers for securing the rod to a window casing or similar object slidably mounted in said groove, and a plurality of brackets each having one end engageable in said dovetailed groove and the other end adapted to support another curtain rod. 30
